COMBINATION WATER NOZZLE AND SPRAY HEAD

William B. Delamater, 9114 Valley View,
Whittier, Calif. 90603

Filed Dec. 4, 1969, Ser. No. 20,352

Term of patent 14 years

Int. Cl. D23—01

U.S. Cl. D23—34

FIG. 1.

FIG. 2.

FIG. 5.

FIG. 3.

FIG. 1 is a top plan view of the water nozzle and spray head, showing my new design;

FIG. 2 is a side elevation thereof, the opposite side being the same;

FIG. 3 is a bottom plan view thereof;

FIG. 4 is an end elevation looking to the right of FIG. 2; and

FIG. 5 is an end elevation looking to the left of FIG. 2. I claim:

The ornamental design for combination water nozzle and spray head, substantially as shown and described.
